UNITED STATES PATENT OFFICE.

JOHN J. O'ROURKE, OF HARRISBURG, PENNSYLVANIA.

RAILWAY-SWITCH MECHANISM.

Application filed October 5, 1925. Serial No. 60,563.

To all whom it may concern:

Be it known that I, JOHN J. O'ROURKE, a citizen of the United States, residing at Harrisburg, in the county of Dauphin and State of Pennsylvania, have invented new and useful Improvements in Railway-Switch Mechanisms, of which the following is a specification.

This invention relates to railway switch mechanisms for railway systems of all kinds, and has particular reference to switch mechanisms of that type adapted to be operated by means under the control of the motorman, engineer or driver of a vehicle for controlling travel between intersecting tracks or lines.

One object of the invention is to provide a mechanically-actuated switch mechanism of simple construction which may be easily and conveniently operated from a vehicle without the necessity of the motorman, engineer or driver leaving his position on the vehicle, and whereby also the use of switchmen at the switch points may be obviated.

Another object of the invention is to provide a switch mechanism which dispenses with the use of springs or other parts liable to get out of order and the throw of which in both directions may be effected from the traveling vehicles.

Still another object of the invention is to provide a switch mechanism which comprises a comparatively small number of parts of durable character and so constructed and arranged as not to interfere with ordinary street or road traffic or to be damaged thereby or rendered inoperative by climatic conditions.

The invention consists of the features of construction, combination and arrangement of parts, hereinafter fully described and claimed, reference being had to the accompanying drawings, in which:

Figure 1 is a top plan view of the switch mechanism arranged at two intersecting tracks and adjusted for directing travel along one of the tracks.

Figure 2 is a vertical longitudinal section on line 2-2 of Figure 1, also showing in section a portion of a vehicle and the switch throwing devices at one side of the vehicle, said devices being arranged in normal position.

Figure 3 is a view similar to Figure 1 showing the switch mechanism adjusted for directing travel along the other track.

Figure 4 is a fragmentary view on an enlarged scale similar to Figure 2, showing the switch throwing device in operation.

Figure 5 is a vertical transverse section taken substantially on the plane indicated by line 5-5 of Figure 2.

Figure 6 is an enlarged detail section taken on line 6-6 of Figure 1.

Figure 7 is a detail view showing a modification.

Referring now more particularly to the drawings, 1, 2 and 2^a, and 3, 3^a and 4 respectively, designate the rails of two intersecting tracks, which may be the tracks of a trunk line, a street railway line, an interurban line, the main railway or other similar railway, on which travel vehicles driven by any suitable power, such as steam, compressed air, electricity, etc. In practice the tracks may be two main divisions, or a main track and a branch track, turn out or siding, of a street railway or other system. For convenience of description, the track formed by the rails 1, 2 and 2^a may be termed a main line track, and the track formed by the rails 3, 3^a and 4 a branch line track.

The continuity of the rail 2 is broken at the point of intersection of the rails 3 and 4 therewith, the short track section 2^a being placed between the ends of the rail members 2 joined to the rail members 3 and 4, one end of the rail 2^a and the juxtaposed end of the rail 3^a being separated from the rails 2 and 3 at their point of junction for free passage of the flanges of the car wheels thereover, as will be readily understood. The end of the rail 3^a which is adjacent to the rail 1 is spaced therefrom and provided with a beveled portion 4' parallel therewith. Between the other end of the rail 2^a and the end of the rail member 2 connected with the rail member 4 is arranged a laterally movable switch tongue 5, said tongue being pivoted at one end to the rail 2^a, as indicated at 6, and having its free end provided with a beveled surface 7, adapted in one position of the switch tongue 5 to engage the adjacent sides of the rails 2 and 4 at their point of intersection. The bevel of the surface 7, however, is such that the tip of this beveled end of the tongue 5 when in such position, as shown in Figure 3, is spaced slightly out of contact with the joined portions of the rails 2 and 4. A guide tube or sleeve 8 is arranged transversely of the rails 1 and 2 at the switch point and suitably fixed in the

100
105
110

road bed, and slidably mounted in this guide 8 is a rod 9, pivoted at one end to the beveled end of the rail 5, as indicated at 10, and having at its opposite end, lying adjacent to the rail 1, an obliquely disposed or beveled contact head 11, for a purpose hereinafter described.

Arranged for cooperation with the laterally movable switch tongue 5 and coacting parts of the rails and the head 11 are longitudinally movable spear-shaped or arrow-head-shaped switch tongues 12 and 13, each having a straight outer face for sliding contact with the adjacent rail 1 or 2 and each having a beveled or inclined inner face 14. These tongues 12 and 13 are carried respectively by rods 15 and 16, on the forward ends of which they are arranged, which rods extend rearwardly on the near side of the switch or junction point for some distance parallel with the rails 1 and 2 and terminate at their rear ends in contact heads 17. Each rod is mounted in a suitable number of supporting guides 18, each guide consisting of a pair of bracket members 19 and 20 bolted or otherwise suitably fastened to the rail, said track members being formed with semi-circular half bearings 21 cooperating to form a bearing for the rod. This construction adapts the bearing members when worn to be removed for ready and convenient replacement. Such construction also permits the lower bearing member of any bearing, which sustains the greatest wear, to be removed independently of the upper bearing member when worn, so that a new lower bearing member may be applied without the necessity of removing and discarding an upper bearing member which may still be in good serviceable condition.

The switch rods 15 and 16 are coupled for sliding motion in unison by a transversely disposed link or lever 22. This link or lever is slidably and pivotally connected at its ends to the rods, so that it may swing past center to opposite angular positions, as shown in Figures 1 and 3, from a straight transverse line, through which movements the rods 15 and 16 may be slid or shifted longitudinally alternately in opposite directions or back and forth, so as to respectively project and retract the switch tongues 12 and 13, or vice versa. At its intermediate point the link or lever 22 is fixed to the top plate of a turntable 23, the bottom plate of which is suitably fastened to the road bed, anti-friction bearings 24 of ball or other suitable type being provided between the turntable plates to reduce friction and wear and permit the upper turntable plate to have requisite freedom of turning movement. When the lever 22 is disposed in the position shown in Figure 1, the switch tongue 12 will be retracted and the switch tongue 13 projected. By this means the tongue 12 is with-

drawn from engagement with the head 11 to allow the tongue 5 to have inward movement and from engagement with the end 4' of the rail 3^a, while the tongue 13 is moved forward between the adjacent rails and the beveled surface 7 of the tongue 5 so that it acts as a spreader wedge to force the tongue 5 inwardly, thus shifting the free end of said tongue 5 away from the joined ends of the rails 2 and 4. The switch mechanism will thereby be arranged to connect the rails 1, 2 and 2^a for straight line travel along the main track, as will be readily understood.

When the link or lever 22 is adjusted to the position shown in Figure 3, the switch tongue 12 is projected and the switch tongue 13 retracted. When so projected the switch tongue 12 will be moved so that its tip lies between the beveled end 4' of rail 3^a and the rail 1 and so that its inclined side 14 engages the head 11, whereby in its forward movement the tongue 13 acting as a spreader wedge will shift the switch tongue 5 outwardly so that its beveled end 7 is moved into contact with the rail members 2 and 4 at their point of junction. The recession or retraction of the switch tongue 13 permits this to be done, although the rearward movement of the tongue 13 is such that when it is retracted its tip lies in the space between the tip of the surface 7 and the junction point of the rails 2 and 4, so that said tongue 13 will be in position for a wedging action on the surface 7 to swing the tongue 5 inward on an ensuing forward movement of rod 16. The movement of the parts to the position shown in Figure 3 breaks the connection between the main line rails 1, 2 and 2^a and makes the connection between the branch line rails 3, 3^a and 4 and the main line rails for travel of the vehicles in one direction from the main line onto the branch line. It will thus be seen that reverse movements of the switch members, including the lever 22 and rails 15 and 16, causes the switch mechanism to be positively thrown for directing the cars or other vehicles for straight line travel on the main track or for directing such cars or vehicles for travel from the main track onto the branch track. A casing 25 is set in the road bed on the inner side of each rail 1 and 2 beneath the rear ends of the rods 15 and 16, each casing being closed by a top plate or cover 26 provided with a longitudinal slot 27 of restricted width. Arranged in each casing 25 is a counterweighted eccentrically pivoted lever 28 having a throw arm 29 provided with a cam surface 29', said arm projecting outwardly through the slot 27 and upwardly on the inner side of the rail 1 or 2. Through its counterweighted action each throw lever normally maintains its arm 29 in an upright position so that its cam face engages with the contact head 17 of the coacting rod 15 or 16, when said rod

is in its rearward or retracted position. The levers 28 are adapted to be independently operated as the case may require to shift the rod 15 or the rod 16 forward, in which forward motion of either rod end the action of its thrust lever the other rod is moved rearwardly or retracted through the lever or link connection 22.

Arranged at each side of the front platform of the car or vehicle 30, or at other suitable points thereon, are duplicate sets of switch throwing devices for actuating the respective rods 15 and 16. As shown, each set of switch throwing devices comprises a bell-crank lever 31 pivoted intermediately on a bracket 32 and having a downturned end 33 and an upturned end 34. The end 33 of the lever 31 is adapted, when depressed, to engage arm 29 of the associated throw lever 28 and shift the same on a rod actuating motion. The upturned end 34 of lever 31 is slidably and pivotally coupled to one end of a motion transmitting lever 35 intermediately pivoted on a bracket 36 and the opposite end of which is slidably and pivotally connected with the stem of a spring-retracted operating member 37, which may be a depressible pedal or foot piece. The normal position of the foregoing parts is shown in Figure 2, and the thrown position of such parts is illustrated in Figure 4. Assuming that the motorman of a car, for example, which is approaching the junction point, desires to route his car from main line travel for which the switch mechanism is set, as shown in Figure 1, for travel therefrom onto the branch line, it will be understood that the motorman depresses the foot piece 37 to project end 33 of lever 31 downward to cause it to strike arm 29 of lever 28, which action will cause rod 15 to be forced forward and rod 16 retracted, with the result of shifting the switch mechanism from the position shown in Figure 1 to that shown in Figure 3. On the other hand, if the motorman, on his car approaching the junction, finds the switch mechanism in the position shown in Figure 3 and his car is routed to travel straight along the main line, he (the motorman) by operating the other set of switch throwing devices may operate lever 28 associated with rod 16 to cause the switch mechanism to be shifted to the position shown in Figure 1. The object of employing the cam surface 29' is to secure an easy and progressive movement to rod 15 without jolts or jars or any tendency to down thrust.

In Figure 7 I have shown a modified form 60 of eccentrically pivoted cam throw lever 28', said lever having a throw arm 29^a and a cam surface 29^b. In this construction the cam surface is formed upon the body of the lever, which may be eccentrically mounted, if desired, upon the side of the rail. This con-

struction may be used with rails of suitable size and when it is not desired to employ the casing 25.

From the foregoing description, taken in connection with the drawings, the construction and mode of operation of my improved switch mechanism will be readily understood and it will be seen that the invention provides a switch mechanism which is simple of construction, inexpensive of production and reliable and efficient in action. Also it will be seen that the invention provides a switch mechanism which, when installed, will not interfere with ordinary vehicular traffic at a junction point, which is of a durable and easily operated type and not liable to be deleteriously affected by climatic changes, and which is equally well adapted for all kinds of railways and to be controlled by the motormen, engineers or drivers of cars or locomotives to control the routing of a car or train.

While the construction disclosed is preferred, it will, of course, be understood that changes in the form, construction and arrangement of parts may be made within the scope of the appended claims without departing from the spirit or sacrificing any of the advantages of the invention.

Having thus fully described my invention, I claim:

1. In a railway switch, the combination with main and branch line rails including a laterally movable switch tongue, of a shifting member connected with said laterally movable tongue, longitudinally movable switch tongues engageable respectively with the laterally movable tongue and shifting member for shifting the said laterally movable tongue in opposite directions, a pair of sliding rods connected with said longitudinally movable switch tongues, a connection between the rods for retracting either rod when the other rod is projected, and means for positively projecting either rod.

2. In a railway switch, the combination with main and branch line rails including a pivoted switch tongue, of a shifting member connected with said tongue, spear-shaped sliding switch tongues having beveled surfaces engageable with the pivoted tongue and shifting member for wedging action for shifting the pivoted tongue in opposite directions, a pair of sliding rods connected with said sliding switch tongues, a connection between the rods for retracting either rod when the other rod is projected, and means for positively projecting either rod.

3. In a railway switch, the combination with main and branch line rails including a pivoted switch tongue, of a shifting member connected with said pivoted tongue, sliding switch tongues engageable respectively with the pivoted tongue and shifting member for shifting the pivoted tongue in opposite di-

rections, a pair of sliding rods connected with said sliding switch tongues, a lever coupling said rods for reverse movements in unison, and means for positively projecting either rod.

4. In a railway switch, the combination with main and branch line rails including a pivoted switch tongue, of a shifting member connected with said pivoted tongue, spear-shaped sliding switch tongues having beveled surfaces engageable respectively with the pivoted tongue and shifting member for shifting the pivoted tongue in opposite directions, a pair of sliding rods connected with said sliding switch tongues, a lever connecting said rods for movement in reverse directions in unison, and means for positively projecting either rod.

5. In a railway switch, the combination with main and branch line rails including a pivoted switch tongue, of a shifting member

connected with said pivoted tongue, sliding switch tongues engageable respectively with the pivoted tongue and shifting member for shifting the pivoted tongue in opposite directions, a pair of sliding rods connected with said sliding switch tongues, connecting means between the rods for shifting one rod rearwardly when the other is positively shifted forwardly and vice versa, throw members engageable with the rods, and means for operating either throw member.

6. In a railway switch, switch mechanism including a horizontal reciprocating switch actuating rod, a counterweighted eccentrically pivoted lever having a convex cam surface for actuating said rod, and a traveling member having means to engage and actuate said lever against its counterweight resistance.

In testimony whereof I affix my signature.

JOHN J. O'ROURKE.
